UNITED STATES PATENT OFFICE.

NOAH J. BECKNER, OF SEATTLE, WASHINGTON.

LACING-HOOK.

1,359,018.

Specification of Letters Patent. Patented Nov. 16, 1920.

Application filed April 28, 1920. Serial No. 377,374.

To all whom it may concern:

Be it known that I, NOAH J. BECKNER, a citizen of the United States, residing at Seattle, in the county of King and State of Washington, have invented certain new and useful Improvements in Lacing-Hooks, of which the following is a specification, reference being had to the accompanying drawings.

This invention relates to lacing hooks such as are used on shoes or other garments for engagement by the laces thereof, and particularly to that variety of lacing hook wherein the head or bill of the hook is pivotally connected to the post or standard of the hook so that it may be opened or closed.

The general objection to lacing hooks as ordinarily constructed and as commonly found on shoes is that the edge of the relatively wide bill of the hook tends to fray garments coming in contact therewith.

The general object of my invention, therefore, is to provide a lacing hook so formed that the head or bill of the hook will normally lie with the head disposed with its edge adjacent to the shoe and, therefore, preventing any fraying of the garment.

And a further object is to provide a construction of this character in which this head is normally shifted to a relatively open position spaced from the face of the shoe to admit the lace, the lace acting by its tension to draw the free edge of the head of the hook downward against the shoe.

5 A further object is to provide a construction of this character in which the head is yieldingly urged away from the shoe by means of a spring contained within the head and is drawn toward the shoe by means of the tension on the lace itself.

A further object is to provide a construction of this character in which the head of the hook is longitudinally and transversely concavo-convex so as to present a rounded 5 surface which will not act to fray the garments, and which also acts as a complete protection against garments being frayed by the post or standard upon which the garment is mounted.

6 Other objects will appear in the course of the following description.

My invention is illustrated in the accompanying drawings, wherein:—

Figure 1 is a perspective view of a shoe 5 having lacing hooks thereon constructed in accordance with my invention;

Fig. 2 is a longitudinal sectional view of one of my lacing hooks closed;

Fig. 3 is a like view to Fig. 2, but showing the lacing hook open;

Fig. 4 is a section on the line 4—4 of Fig. 3;

Fig. 5 is an under side plan view of the lacing hook and its base.

Referring to these drawings, it will be seen that my improved hook comprises a base 10 which is adapted to be riveted or otherwise attached to the shoe or other garment A by means of the rivet a. This base plate 10 at one end is reduced in diameter and provided with upwardly and forwardly extending shanks constituting ears 11 spaced from each other preferably throughout their entire extent, though not necessarily so. These ears are extended upward and forward so that the forward edge of the ears is inwardly curved, as at 12, and the ears adjacent their upper ends are provided with transverse, alining perforations 13. 65 70 75

The head of the hook is formed of an outer or upper shell 14 of thin sheet metal, preferably enameled, this shell being longitudinally concavo-convex, with the convex side upward, and transversely concavo-convex, as is illustrated most clearly in Figs. 2 and 4. The head is completed by a metallic plate 15 which is approximately oval in form, as is the shell 14 or cap, and which is formed with ears, the blank being formed with the outwardly and rearwardly projecting portions 16 constituting ears, these ears being folded over flat upon the upper face of the plate 15, as is illustrated most clearly in Fig. 4, and then being upwardly extended, as at 17, on each side of the standards 11. 80 85 90 95

A pivot pin, rivet, bolt or equivalent element 18 is disposed through these ears 17 and through the openings 13 in the posts 11. Thus the plate 15 is pivoted upon the posts for limited oscillation. The middle or the rear portion of the plate 15 is curved downward and forward, as at 19, and this portion extends across the front of the post. Preferably, the plate 15 extends rearward on each side of the posts 11, as at 20. The cap or shell 14 has its edge inwardly bent into engagement with the plate 15 and is crimped around said plate and soldered or otherwise attached thereto. Thus, this head formed by the cap or shell 14 and the plate 15 is hollow and the posts 11 extend up into the rear portion of this hollow head. Disposed 100 105 110

between these posts 11 and suitably held therein is the rear end of a spring 21, which spring is upwardly bowed and engages at its forward end with the forward end portion of the shell or cap 14. This spring tends to raise the free end of the head formed by the shell 14 and the plate 15 to the position shown in Fig. 3.

If now the lace B be passed around the portion or tongue 19 and drawn taut, the tension of the lace will so draw upon the tongue 19 as to pull the free end of the head downward to the position shown in Fig. 2 into very close relation to the leather of the shoe or of the surface of the garment. Immediately upon a relaxation of this tension, however, the spring 21 will act to raise the free end of the head and depress the rear end thereof to the position shown in Fig. 3, thus permitting the free removal of the lace. It will thus be seen that the hook opens and closes automatically as the lace is inserted or removed from the hook.

It will be noted that with this construction the plate 15 which supports the shell 14 is transversely braced by the portions 16 which are bent over upon the face of the plate 15 so that this plate is strengthened thereby at the point where the pivot is formed. It will further be seen that it is relatively easy to attach plate 15 to the posts 11, then place the spring in position, and then place the cap 14 over the plate 15 and engage it therewith along its edges. It will further be noted that a relatively strong bearing is secured for the pivot pin 18 because of the four thicknesses of metal through which the pin passes. It is, of course, obvious that the posts or standards 11 might be integral at their lower portions and a hole be bored for the shank of spring 21.

While this lacing hook is designed particularly for use on boots and shoes, yet it is obvious that it might be used in any situation where such a lacing hook is desirable. It might be used for gaiters or other articles of clothing. It is obvious that the lace may be readily withdrawn from engagement with the hook by simply slackening the strain on the lace, and pulling the lace out from beneath the bill or body of the hook. Inasmuch as the tongue 19 is transversely curved, the lace will not come in contact with a relatively thin and relatively sharp-edged tongue and, therefore, will not be frayed. Further, as the head of the hook formed by the shell 14 and the part 15 entirely conceals the shank formed by the standards 11, a more attractive character will be given to the hook than otherwise would be the case.

I claim:—

1. A lacing hook of the character described comprising a base, a supporting

shank extending upward therefrom, a head forming the bill of the hook and pivoted to the shank, the head being formed with a hook-shaped tongue extending downward and forward beneath the pivotal axis of the head and with which the lace is adapted to engage to turn the head to a closed position, and a spring engaged at one end with the shank and extending into and housed by the head and acting to urge the free edge of the head upward.

2. A lacing hook of the character described comprising a base, a shank extending upward therefrom, a head forming the bill of the hook, said head being transversely and longitudinally concavo-convex and being hollow and having its convex side facing the base, said head being pivoted intermediate its ends to the shank and being formed with a hook-shaped tongue extending downward and forward beneath the pivotal axis of the head and with which the lace is adapted to engage to turn the head to a closed position, and a spring attached to the shank and extending into the hollow head and urging the free end of the hollow head away from the base.

3. A lacing hook of the character described comprising a base having upstanding shanks at one end spaced from each other at their upper ends, a hollow head inclosing the upper ends of the shanks, a pivot pin extending through the shanks, the head having ears disposed on each side of the shanks and through which the pivot pin passes, the under face of the head adjacent the shank being reversely curved and formed to provide a tongue extending rearward toward the shank, then downward and outward whereby to be engaged by a lace, and a spring having one end engaged with said shanks and its free end engaged with the free end of the head and said spring being entirely inclosed by said head.

4. A lacing hook of the character described comprising a base having outwardly extending shanks at one end, the shanks being forwardly curved, a head comprising a lower plate formed to provide two ears embracing the shanks and pivoted thereto and between said ears with a downwardly and forwardly extending hook disposed in front of said shanks and adapted to be engaged by a lace, a transversely and longitudinally concavo-convex cap attached at its margins to said plate and extending over the rear portions of the shanks, and a spring attached at one end to said shanks and at its free end engaged with the said cap and acting to urge the head to an open position.

5. A lacing hook of the character described comprising a base having outwardly extending shanks at one end, the shanks being forwardly curved and spaced from each other, and a head comprising an inner

plate formed at its margin and adjacent its rear end with laterally extending portions and lateral lugs, the material of said lugs being then extended inward to the shanks and then outward parallel to the shanks to form ears, a pivot pin passing through said ears and through the shanks and pivoting the plate to the shanks, that portion of the plate immediately in front of the shanks being extended downward and forward in a curve and being adapted to be engaged by a

lace, a concavo-convex cap extending over the plate and extending over the rear portions of the shanks and attached at its margins to the plate, and a spring engaged at 15 one end with said shanks extending beneath the pivot pin and at its free end engaging with the cap, and urging the free end of the head upward.

In testimony whereof I hereunto affix my 20 signature.

NOAH J. BECKNER.
